[57] ABSTRACT

In an incandescent lamp, particularly projection lamps of large luminosity, both ends of an upper glass bar for holding down supporting hooks, which hangingly support segmented coils of an incandescent filament, are welded to specified positions on the inner face of the bulb, so as to secure the filament rigidly and durably.

FIG.1.

FIG.3.

FIG.2(a).

FIG.2(b).

INCANDESCENT LAMP

BACKGROUND OF THE INVENTION

This invention relates to an incandescent lamp, in particular to the supporting (propping) construction of its filament. Among such incandescent lamps, this invention concerns those for spot lighting or narrow beam projecting, especially lamps of large luminosity.

For the incandescent lamp, it is very important, needless to say, that its incandescent filament must be rigidly and securely supported in its bulb. Such a requirement is especially keen for a lamp which is designed for spot lighting, i.e., for narrow beam projecting purposes, of the kind which is mounted in a specified projector or wherein the bulb itself encloses a specified reflector. Such a bulb is designed to determine the positional relations between said reflector and a filament installed in a specified area so as to project beams from the filament in a specified direction.

A typical example of the support construction adopted in the prior art comprises two large lead-in wires extending in parallel from the stem, and two insulating bars bridging said lead-in wires at their top ends and stem parts, respectively. Also, a specified number of supporting hooks are provided, each having one end embedded and fixed in said upper insulating bar and the other hooked end hangingly holding the filament coils. In such a construction, however, for lamps of larger output and higher power, the filament must have an increasingly greater size and weight, and hence, it is necessary to proportionately enlarge the diameter of the two lead-in wires in order to prop the filament rigidly in the right position. Such enlarging of the diameter consequently invites mechanical and thermal weakening of the parts where said lead-in wires contact the inner glass face of the bulb, thereby hampering the manufacturing process.

SUMMARY OF THE INVENTION

This invention purports to provide a simplified and reliable technique for manufacturing incandescent lamps, especially for beam projecting, i.e., spot lighting purposes and in particular those enclosing halogen gas, and for rigidly holding filament inside the bulb.

Another object of this invention is to provide incandescent lamps having high efficiency, owing to a construction wherein emission from the filament is not interrupted by the lead-in wires.

A further object of this invention is to provide incandescent lamps of the above-described kinds embodying greater freedom in designing as small a means as possible for propping the filament inside the bulb, thereby making it possible to reduce the size of the bulbs.

In order to attain such objects as mentioned above, the present invention is characterized by fixing the upper insulating bar to the inner face of a bulb by welding, namely by heating, melting and then connecting.

BRIEF DESCRIPTION OF THE DRAWING

FIG. 1 is a perspective view of a halogen projection lamp embodying the present invention;

FIG. 2a is a front view partially in section of a halogen projection lamp embodying the present invention;

FIG. 2b is a side view partially in section of the lamp in FIG. 2a; and

FIG. 3 is an exploded perspective view showing component parts of a halogen projection lamp embodying

the present invention, for the purpose of explaining one method of the process of assembling the same.

DETAILED DESCRIPTION OF THE INVENTION

FIG. 1 shows a halogen projection lamp, embodying the present invention. In FIG. 1 an enclosure 1 made of quartz glass encloses an incandescent filament 2, a pair of lead-in wires 3, and a filament supporting means 4. The enclosure 1 has a cylindrically shaped trunk portion which extends through a tapered part 21 and ends in a pair of tubes 6. The enclosure 1 further encloses a mixture of argon gas and a specified quantity of methylene bromide and hydrogen bromide.

The filament 2 is made of a tungsten wire and formed into six segmented coils 5 which are arranged in a zig-zag row on a level plane in such a manner that the axes of the coils are disposed substantially in parallel. The pair of lead-in wires 3, which feeds the current in the filament 2, pass in airtight condition through the wall of the enclosure at the tubes 6 at the bottom of the enclosure 1.

The filament-supporting means 4 comprises an upper quartz glass bar 7 disposed at right angles to the axis of the bulb and three supporting hooks 8 made of tungsten wires, one end of each being embedded in and fixed to said upper glass bar 7. Both ends 9 and 9' of said upper glass bar 7 are welded on the inner face of the enclosure 1. The other ends of said supporting hooks 8 are bent up to hang down and engage upper spacers 10 which are the noncoiled parts formed between the segmented coils 5. The coils are also secured underneath at lower spacers by lower supporting hooks 15. The ends 11 and 11' of the filament 2 are windingly connected to respective ends of linking wires 13 which are in turn wound on the respective lead-in wires 3 near their upper ends 12. The other ends of the linking wires 13 are respectively fastened to a lower quartz glass bar 14, into which said lower supporting hooks 15 of tungsten wires are fixed. The lower supporting hooks 15 pull down the lower spacers of the filament 2. The pair of lead-in wires 3 need not be extended all the way along the filament assembly up to the upper glass bar as in the conventional projection lamp, but the lead-in wires 3 terminate slightly below the lower ends of the segmented coils 5.

As described above, the upward propping of the filament 2 is accomplished by the upper glass bar 7 firmly fixed to the upper portion of the inner face of the enclosure 1. Hence, the construction is very rigid and secure, as well as strong against vibrations and shocks. Moreover, the lead-in wires 3 can be short and their upper ends need only hold the lower ends of the segmented coils propped by the upper glass bar 7. Therefore, the lead-in wires 3 dispense with the need of the conventional construction to rigidly support the heavy weight of filament, etc., by long wires passing beside the filament. Accordingly, the lead-in wires can be much finer and shorter, and hence, the work required for passing the lead-in wires 3 into the bulb can be simplified.

FIG. 2 shows a second example of the invention. In FIG. 2 most of the parts are constructed in a similar manner to those of the first example shown in FIG. 1. However, in this second example, the lead-in wires 3 are so short as to terminate beneath the filament 2, and they are situated coaxially with the outermost segmented coils 16 at both sides. The lower ends of the

segmented coils 16 at both sides, namely, both ends of the filament coils 2 are formed as connecting coils 17 wound around and connected to the upper ends of the lead-in wires 3. A lower glass bar 14 is fixed to the middle part of the lead-in wires 3 which penetrate the glass bar 14. The glass bar 14 has supporting hooks 15 supporting lower spacers 10' of the filament 2. The parts of the lead-in wires 3 embedded in the lower glass bar 14 are slightly bent or have rugged surfaces in order to be firmly fixed. A base 18 is fixed to the stem part.

An actual example of the embodiment of FIG. 2, a halogen lamp of 3KW/100V performance is as follows: the diameter of the enclosure is 45 mm, and the length from the top to the bottom face of the base is 200 mm. The filament consists of six coil segments, each being wound for 26.5 turns of 1.6 mm inner diameter and 1 mm pitch with 0.665 mm tungsten wire. The spacers 10, . . . 10', . . . which are the non-coiled parts between the segments are 6 mm long, respectively. The end spacers 111 connected to the lead-in wires 3 are 5 mm long, and the connecting coils 17 are similar in diameter and pitch to the segmented coils, being 6 mm in length. The segments of the coils are so arranged that the distance between the axes of the segments on both extreme sides (i.e., the axes of both outermost segments) is 25 mm. The upper and lower glass bars 7 and 14 are of roughly 6 mm diameter and the supporting hooks 8 and 15 are of 0.7 mm diameter tungsten wire.

The end spacers 111 may be connected to the upper ends of the lead-in wires 3 by placing their ends to ends contacting each other and continuously covered by connecting coils.

As a result of the above-mentioned construction, the lamp of the second example has the following advantages besides the advantages of the first example.

Since the upper ends of the lead-in wires 3 are situated coaxially with the segment coils 16 of the extreme sides of filament 2, the distance between the two lead-in wires 3 can be made very short, and consequently, the diameter of the enclosure can be made small. This is very advantageous as the halogen lamp in which the volume of the enclosure is strictly restricted by its function.

This invention is also applicable to any incandescent lamps other than halogen lamps, and can enjoy the advantage that the radiation from the filament is hardly shielded or absorbed by the lead-in wires supporting the filament, and can enjoy the resultant advantage of high efficiency of electric power to luminous output conversion.

The process of assembling or making the abovementioned lamps will be explained below with reference to FIG. 3. As shown in FIG. 3, which is an exploded perspective view of the lamp of FIG. 2, a bulb 19, a glass bar 7 having several supporting hooks 8, a filament assembly 20 and a tapered part 21 are provided. The bulb 19 in a glass cylinder with an evacuation tube 22 at the top and with a broad lower opening. The upper glass bar 7 is made by the process of at first, holding the fixed ends of the supporting hooks 8 between a pair of glass bars, and then heating and pressing the glass bar so that the two glass bars are united into one glass bar with the ends of the supporting hooks 8 embedded therein. The filament assembly comprises the filament 2, a pair of the lead-in wires 3, the glass bar 14 supported by the lead-in wires 3, the lower supporting hooks 15 fixed to the glass bar 14, and a pair of glass tubes 6, the lower

ends of which are airtightly secured to the leading-in wires 3. The tapered part 21 is a short glass cylinder having an upper open end to be connected to the lower open end of the bulb 19, the upper open end of the tapered tube having a diameter just to fit inside the lower open end of the tube. The tapered part has two lower openings to be connected to the upper ends of the tubes 6, the lower openings having a diameter to fit outside the upper ends of the tubes 6.

10 The first step of assembling the lamp is to secure the upper glass bar 7 at a suitable location in the upper part of the bulb 19. The securing is made by holding the glass bar 7 by a jig at a suitable position and heating the surface of the bulb at the position to be welded (melted and secured) by gas flames, and then by pressing the half-melted part of the bulb wall toward the ends of the glass bar 7.

15 The second step is to insert the filament assembly 20 into the bulb and hang the spacers between segmented coils 5 of the filament 2 on the supporting hooks 8.

20 The third step is to cover the tubes 6 and filament assembly with the tapered part 21, and to seal the lower opening of the bulb 19 and the upper opening of the tapered part 21, and to seal the lower openings of the tapered part 21 and the upper part of the tubes 6. The sealings are made by heating and welding the parts to unite them to each other.

25 The fourth step is to evacuate the sealed bulb, injecting argon gas containing a specified small amount of methylene bromide, and sealing the evacuation tube 22 by heating and pinching.

30 When desired, a base 18 is secured at the lower end of the bulb.

35 While I have shown and described several embodiments in accordance with the present invention, it is understood that the same is not limited thereto but is susceptible of numerous changes and modifications as known to a person skilled in the art, and I therefore do not wish to be limited to the details shown and described herein but intend to cover all such changes and modifications as are obvious to one of ordinary skill in the art.

What is claimed is:

40 1. An incandescent lamp comprising a glass enclosure, an incandescent filament enclosed in said glass enclosure, a pair of lead-in wires extending through said glass enclosure for feeding electrical current to said filament, an upper glass bar having its ends welded to the inner face of said glass enclosure at one end thereof, a lower glass bar being secured in position within said glass enclosure at the other end thereof while having its ends left free from said glass enclosure, and supporting hooks extending between said upper glass bar and said filament and between said lower glass bar and said filament for supporting said filament in a desired position.

45 2. An incandescent lamp as defined in claim 1 wherein the upper ends of said lead-in wires terminate below said filament.

50 3. An incandescent lamp as defined in claim 2 wherein said filament is formed into several segmented coils having their axes substantially parallel to the lamp axis, and the upper ends of said lead-in wires being situated coaxially with the outermost segmented coils of the filament.

55 4. An incandescent lamp as defined in claim 3 wherein said lower glass bar is fixed by said pair of lead-in wires penetrating therethrough.
